Hibbent High Pressure 8 Inch Rainfall Shower Head/Handheld Showerhead Combo/Adjustable Shower Extension Arm, 7-Spray, 71 Inch Shower Hose, Adhesive Shower Head Holder, Matte Black, available in Amazon.com, customer photo review oldest date Apr. 23, 2023[online], [site visited Oct. 9, 2024], Available from the internet URL: <https://www.amazon.com/Hibbent-Pressure-Showerhead-Adjustable-Extension/product-reviews/B0BXN9F9LD> (Year: 2023).*

Primary Examiner — George J Ulsh*Assistant Examiner* — Kathryn Elizabeth Zieno(74) *Attorney, Agent, or Firm* — Jose Cherson Weissbrot(57) **CLAIM**

The ornamental design for an extension rod for shower as shown and described.

DESCRIPTION

FIG. 1 is a perspective view of an extension rod for shower showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a left side view showing alternate configuration of my new design.

Broken lines in the drawings depict portions of the extension rod for shower that form no part of the claimed design.
